UNITED STATES PATENT OFFICE.

AUGUST SIEGMUND, OF LUDWIGSHAFEN, GERMANY, ASSIGNOR TO THE
BADISCHE ANILIN AND SODA FABRIK, OF SAME PLACE.

PROCESS OF DYEING.

SPECIFICATION forming part of Letters Patent No. 659,556, dated October 9, 1900.

Application filed July 24, 1900. Serial No. 24,712. (No specimens.)

To all whom it may concern:

Be it known that I, AUGUST SIEGMUND, 5
dyer, a subject of the King of Prussia, German
Emperor, residing at Ludwigshafen-on-
the-Rhine, in the Kingdom of Bavaria and
Empire of Germany, have invented new and
useful Improvements in Processes of Dyeing
Wool, of which the following is a specification.

In the art of wool-dyeing it is often very
desirable to combine perfect level dyeing with
the highest possible clearness and brilliancy
of shade attainable, especially where delicate
shades are demanded. This is particularly
true in the case of zephyr yarns. It has long
been known that no matter how carefully the
wool has been bleached prior to dyeing the
shade obtained is always more or less sad.
This sad appearance can be removed only by
the old and well-known operation of stoving—
that is, by subjecting the dyed and whizzed
goods, whether loose, spun, or woven, to a
treatment with sulfur dioxide in the sulfur-
chamber. The stoving operation is absolutely
essential for certain dyestuffs when used
where the highest possible brilliancy is re-
quired, and without such treatment many
dyestuffs would be inapplicable to this branch
of the art of dyeing—for example, rhodamin,
auramin, &c. It is obvious that only such
dyestuffs are available for this purpose as are
fast against sulfur dioxide and which are con-
sequently known in the art as being “fast to
stoving.” It is also obvious that this stoving
operation increases the time necessary for the
dyeing of a certain quantity of material and
also adds to the cost of manufacture of the
dyed goods. Moreover, this old process is at-
tended with an expenditure of a very great
amount of care, brought about by the diffi-
culty it causes in dyeing to shade, inasmuch
as it frequently causes a change in shade or
a lightening or both, which is exceedingly
troublesome and irksome to rectify and so
causes an extra expenditure of labor and dye-
stuff. The rectification of such a shade is an
operation not generally attended with suc-
cess.

The object of this invention is to obviate
this additional and irksome operation of stov-
ing and the attendant labor of bringing the
stoved goods to shade, and thus to simplify

and to reduce the cost of the process of ob-
taining these highly-desirable level and clear
shades.

This invention is based upon the new and 55
striking observation that all the advantages
which dyed goods show after having been sub-
jected to stoving are obtained by adding to
the dye-bath simultaneously with the dyestuff
and chemicals sulfurous acid or such sub- 60
stances as will develop sulfurous acid under
the conditions prevailing in the dye-bath,
dyeing, and finishing, as usual, without stov-
ing. It has also been observed that there is
a decided gain in clearness of shade as well 65
as also a saving in the amount of dyestuff
required to produce a certain shade as against
the old process. In addition to this there is
also in many cases the great advantage that
the dyer can dye to shade directly and with- 70
out running the risk of being obliged to sub-
mit the stoved goods to a subsequent and
troublesome treatment with dyestuff in order
to get to shade. These effects and advan-
tages are not to be obtained by subjecting the 75
dyed goods to a bath of sulfurous acid, whether
the sulfurous acid be added to the dye-bath
after it has been exhausted or whether the
dyed goods are treated in the well-known way
in a separate bath containing sulfurous acid, 80
or in that case a lightening of the shade with-
out any increase in brilliancy results—that
is, the dyestuff is stripped from off the fiber.

In the following an example is given as to
how this invention can be applied. For one 85
hundred pounds of goods prepare a dye-bath
as follows: three hundred and seventy-five
(375) gallons of water, five (5) pounds of bi-
sulfite of soda of 38° Baumé, three and a
quarter (3 $\frac{1}{4}$) ounces of rhodamin 3B, ten (10) 90
pounds of Glauber salts, and two (2) pounds
of sulfuric acid of 66° Baumé; enter, bring to
boil, and dye to shade.

In place of the rhodamin in the preceding
example any of the other dyestuffs which 95
are fast to stoving may be used. Among
these may be particularly mentioned auras-
min, methyl violet, victoria blue, palatin scar-
let, fast yellow, acid violet 4R, alkali violet,
victoria night-blue, &c.

What I claim is—

1. The process of dyeing wool, which con-

sists in dyeing the material in a bath containing a dyestuff which is fast to stoving and sulfurous acid, all substantially as described.

2. The process of dyeing wool, which consists in dyeing the material in a bath containing rhodamin and sulfurous acid, all substantially as described.

In testimony whereof I have hereunto set my hand in the presence of two subscribing witnesses.

AUGUST SIEGMUND.

Witnesses:

BERNHARD C. HESSE,

JACOB ADRIAN.
